UNITED STATES PATENT OFFICE.

HENRY R. SIEVERKROPP, OF RACINE, WISCONSIN.

BICYCLE-PEDAL ATTACHMENT.

SPECIFICATION forming part of Letters Patent No. 634,592, dated October 10, 1899.

Application filed December 19, 1898. Serial No. 699,641. (No model.)

To all whom it may concern:

Be it known that I, HENRY R. SIEVERKROPP, a citizen of the United States, and a resident of Racine, in the county of Racine 5 and State of Wisconsin, have invented certain new and useful Improvements in Bicycle-Pedal Attachments; and I do hereby declare that the following is a full, clear, and exact description thereof.

10 My invention has for its object to facilitate speeding and control of a bicycle; and it consists in a simple, economical, strong, and durable pedal attachment similar to that which is hereinafter particularly set forth with reference to the accompanying drawing and subsequently claimed.

The drawing is a perspective view of a partly-broken bicycle-pedal attachment in accordance with my invention.

20 Referring by letter to the drawing, A indicates each of a pair of parallel spring-metal plates that are designed for detachable connection with the front and rear of a bicycle-pedal, as by means of the bolts *b*, nuts *c*, and washers *d* herein shown.

Each plate A is bent to form a pair of parallel split sleeves longitudinally thereof, and in adjustable engagement with the sleeve portions of the plates are horizontal ends of 30 otherwise upwardly and inwardly bent yokes B, each of which is herein shown made from a single stiff wire and preferably shaped to avoid sharp angles. Compression of the plate-sleeves serves to hold the yokes in adjusted position, and this compression is had by the means employed to hold the plates in detachable connection with the pedal.

The plates A and yokes B constitute an adjustable foot-clip attachment for a bicycle-40 pedal of any well-known variety, and clips similar to those herein set forth not only insure foothold on bicycle-pedals to which they

are connected, but they also make it possible for bicycle-riders to exert their greatest lifting strength upon said pedals.

As herein shown, each yoke of a foot-clip in accordance with my present invention may be provided with a sheet-metal shield C, crimped on said yoke to present a smooth inside surface, thus increasing the foot-opposing surface and preventing the wire of the yoke from being hurtful.

Having thus described my invention, what I claim as new, and desire to secure by Letters Patent, is—

1. A foot-clip comprising a pair of plates attachable to the front and rear of a bicycle-pedal, and a pair of upwardly and inwardly bent stiff-wire yokes in adjustable connection with the plates.

2. A foot-clip comprising a pair of plates attachable to the front and rear of a bicycle-pedal, a pair of upwardly and inwardly bent stiff-wire yokes in adjustable connection with the plates, and a metal shield crimped on each 60 yoke to present smooth inside foot-opposing surface.

3. A foot-clip comprising a pair of spring-metal plates, each bent to form a pair of parallel sleeves longitudinally thereof, clamping 70 devices for connecting the plates with the front and rear of a bicycle-pedal, and a pair of upwardly and inwardly bent stiff-wire yokes having their ends adjustable in said sleeves.

In testimony that I claim the foregoing I have hereunto set my hand, at Racine, in the county of Racine and State of Wisconsin, in the presence of two witnesses.

HENRY R. SIEVERKROPP.
